UNITED STATES PATENT OFFICE.

EDWARD DAMMANN, OF ST. LOUIS, MISSOURI.

WIND OR WATER POWER.

1,313,621.

Specification of Letters Patent.

Patented Aug. 19, 1919.

Application filed November 13, 1918. Serial No. 262,371.

To all whom it may concern:

Be it known that I, EDWARD DAMMANN, a citizen of the United States, residing at St. Louis, in the county of St. Louis and State of Missouri, have invented certain new and useful Improvements in Wind or Water Power, of which the following is a specification.

This invention relates to fluid current 10 motors, and more especially to rotary motors mounted on a vertical axis and having feathering blades; and the object of the same is to produce a fluid power unit especially applicable for use with wind or 15 water, and wherein the impelling fluid actuates the rotor both by impact and by pressure during a full half of the revolution thereof.

A further feature of the invention is that 20 of the feathering blades or paddles, and a yet further feature is the means for regulating the inlet of the motive fluid.

Details are set forth in the following specification and claims, and attention is 25 invited to the drawings, wherein:

Figure 1 is a plan view of this structure with the top omitted, showing the rotor as mounted on a substantially circular platform.

Fig. 2 is a side elevation of this invention showing the rotor as almost completely housed within a casing, and illustrating especially the track or cam on which the roller at the outer corner of each paddle or 35 blade travels.

Fig. 3 is a perspective view of yet another form of this invention with the track and rotor omitted, and in which the walls of and partition within the rotor end of the 40 structure are mounted upon a comparatively large platform.

Fig. 4 is a perspective detail of the rotor and one paddle or wing.

Considerable latitude is possible with 45 respect to the housing or casing of this machine, the character, velocity, and volume of the motive fluid necessitating modifications therein as will be clear. For instance the bottom or platform 1 of the housing 50 shown in Fig. 1 is substantially circular, and the top which is there omitted would be the same; the housing or casing in Fig. 2 is box-shaped at the front and includes a bottom or platform 3 which extends be-

neth the rotor, and a top 4 which over- 55 lies the rotor to the point 5, the rotor itself here having a top 6; and the bottom or platform 7 in Fig. 3 not only underlies the rotor but extends forward of the same in fan-shape to permit adjustment of the doors or 60 gates as described below, the top in this case being preferably about of the same shape. In any event, however, the fixed walls are two in number, respectively indicated at 8 and 9, and each is struck on a 65 curve and extends around the rotor chamber for a little more than ninety degrees, these walls being set about opposite each other. Between the inner end of the front wall 8 and the front end of the rear wall 9 is 70 an inlet opening 10 disclosed clearly in Fig. 3 and designated by the arrow 11 in Fig. 1. Between the rear end of the front wall 8 and the inner end of the rear wall 9 is an outlet opening designated 12 in Fig. 75 3, indicated by the arrow 13 in Fig. 1, and hidden by the paddle at the right of Fig. 2. The numeral 14 designates a rigid radial partition extending along one side of the outlet, and over which partition the several 80 paddles must pass as described below. Hinged at 15 to the front end of the fixed walls are gates or doors 16 and 17 which may be adjusted over the bottom or platform, between the bottom and top, or even 85 where there is no bottom and top. While any form of adjustment is permissible, I prefer to provide these gates or doors with openings or holes 18 in their upper edges to receive pins 19 which will pass through 90 the top 4 if there be a top to the casing, or will pass through corresponding holes in rods or bars 20 which are appropriately pivoted as at 21 and 22 to some fixed portion of the device. A top bar 23 also having 95 holes 24 may connect the forward ends of the doors or gates, the same pins 19 being employed or others numbered 29. The purpose is to permit the gates or doors 16 and 17 to be swung on their hinges 15 so as to 100 control the flow of fluid into the inlet opening 10, whether said fluid be air or water and whatever its direction of approach. The fluid entering the casing between the walls 8 and 9 is applied to the rotor yet 105 to be described and passes around therein and out at the outlet opening at the rear of the casing and at one side thereof, but

the volume of fluid admitted is to a large extent controlled by the setting of said doors or gates.

The rotor itself is perhaps best seen in Fig. 4. An upright shaft 30 is mounted through the bottom 1 at a central point between the walls 8 and 9 as indicated at 31 in Fig. 3, and it may or may not have a bearing in the top of the casing if the latter has a top. A bearing is indicated in Fig. 2 by the numeral 32, below which the shaft is extended for carrying a driving wheel or otherwise performing service. It is obvious, however, that the shaft could rise from the casing and the driving wheel be applied to its upper end. Within the casing this shaft carries a plurality of spokes indicated at 33, their outer ends being connected by a ring 34. Over these spokes and rings in Fig. 2 the rotor has a top plate 6, but in other views the rotor has no such top plate. It will need none when there is no top to the casing, and it needs no bottom plate because the casing always has a bottom. The ring is supported and braced by braces 35, each extending obliquely from the outer end of a spoke to a point on the shaft 30 just above the opening 31 in the platform through which the shaft passes. By preference there are four spokes and four braces. Hingedly hung at 36 on each spoke is a wing or paddle 37, preferably consisting of a frame with suitable braces across it, and a light fabric sheet stretched within the frame. It is important to note from Fig. 4 that the wing is hung from the spoke in rear of the brace 35 in the direction of rotation which is indicated by the arrow, and therefore the wing when it hangs pendant rests against the brace and cannot be moved forward, although it may be folded backward as indicated in dotted lines. At its lower outer corner the wing carries a roller preferably in the shape of a ball 38. The spokes and the wing 34 travel over the partition 14, and in order that the several wings shall pass over the frame when they reach it there is provided a track or cam on which the several rollers travel. This track rises at 41 from the point 40 rather abruptly to the point 42, whence it extends horizontally at 43, over the partition 14 as seen in Fig. 2, to the point 44 inside the front wall 8, and thence it descends again as at 45 to about the point 46 in Fig. 1, where it is level with or perhaps carried upon the bottom of the casing or platform. In fact, the track might be omitted through the right half of the rotor portion of the casing as shown in Fig. 1, and the spherical roller 38 allowed to travel upon the base or platform 1.

With this construction of parts, the operation is as follows: The adjustment of the doors or gates 16 and 17 need hardly be amplified. They will be set toward the pre-

vailing direction of the wind if it be wind that is employed as the fluid motive agent, or they will be set to receive the current of a stream of water, and they will be adjusted farther apart or closer together according to the volume of wind or water it is desired to admit to the rear portion of the casing. As above stated, considerable latitude is allowed the manufacturer in the formation of this casing, especially at its front end. The motive fluid enters the inlet opening 10 as indicated by the arrow 11 in Fig. 1, and we may assume that the stream of fluid occupies the full width of the space between the hinges 15 and 15. The paddle or wing indicated at *a* is just moving past one of said hinges, and some of the fluid catches behind this wing and carries it forward to the point *b*, the bulk of the fluid carrying the wing *b* forward to the point *c* and of course having less and less effect upon the second wing as it increases in its effect upon the first wing *a*. By the time the wing *b* has reached the point *c* the wing *d* has reached the point *a*, but the power of the motive fluid agent is exerted on two wings constantly and throughout a full half revolution of the rotor. As any wing passes the point 40 its roller 38 begins to ascend the rise 41 of the track, and the motive fluid is permitted to flow out the outlet opening. While the roller is passing along the horizontal stretch 43 in Fig. 2, the wing stands horizontal as there shown and as best illustrated in Fig. 1, and in such position it can easily pass over the partition 14. The latter is useful for preventing eddies or currents of the outflowing fluid from being carried around with the rotor, producing the undesirable churning effect so prevalent in machines of this type. Therefore there is no moving motive fluid affecting the wing which passes over the partition and while it is descending along the fall 45 of the track; and just as it becomes again vertical at the point *a*, it passes from behind the inner end of the front wall 8 and receives another blast of air or water as described above.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a device of the class described, the combination of a casing comprising a base having a pair of fixed walls thereon, said walls being curved throughout their entire length in the arc of a circle, one of said

- walls being shorter than the remaining wall, said short wall having a rigid partition extending at substantially right angles thereto and projecting in the direction of the remaining wall, elongated gates hingedly mounted upon the ends of said fixed walls, bars pivotally mounted upon said short fixed wall and being adjustably connected to said gates adjacent their outer ends, a top bar directly mounted upon said gates, whereby the gates will be adjustably held in set positions to direct fluid into the interior of said casing, and a rotor revolvably mounted within said casing.
2. In a device of the class described, the combination of a casing including a short transversely extending partition, a rotor revolvably mounted within said casing and including an upright shaft having radiating spokes, paddles hingedly mounted upon said spokes and depending therefrom, diagonal braces fitting in the rear of said paddles as the rotor revolves to reinforce the same so that as fluid pressure bears upon the paddles the rotor will revolve, the lower outer edges of said paddles being unobstructed, rollers carried upon the lower outer edges of said paddles, and a track comprising a horizontal portion extending above said partition and downwardly curved end portions, whereby as the rotor revolves, said rollers will strike said track and will ride upwardly to hold the paddles in horizontal position as the same pass above said partition and then allow the paddles to move downwardly to receive the force of fluid pressure entering the casing.
3. In a device of the class described, the combination of a casing comprising a base having a pair of fixed walls thereon, said walls being curved throughout their entire length in the arc of a circle, one of said walls being shorter than the remaining wall, elongated gates hingedly mounted upon the ends of said fixed walls, bars pivotally mounted upon said short fixed wall and being adjustably connected to said gates adjacent their outer ends, a top bar directly mounted upon said gates, whereby the gates will be adjustably held in set positions to direct fluid into the interior of said casing, and a rotor revolvably mounted within said casing.
- In testimony whereof I affix my signature in presence of two witnesses.
- EDWARD DAMMANN.
- Witnesses:
- MICHAEL MUICH,
HUGO N. FEITZ.
